UNITED STATES PATENT OFFICE.

HOWARD E. HARBAUGH, OF KENOSHA, WISCONSIN.

KNITTING-MACHINE.

SPECIFICATION forming part of Letters Patent No. 681,546, dated August 27, 1901.

Application filed February 14, 1901. Serial No. 47,373. (No model.)

To all whom it may concern:

Be it known that I, HOWARD E. HARBAUGH, a citizen of the United States, residing at Kenosha, in the county of Kenosha and State 5 of Wisconsin, have invented certain new and useful Improvements in Circular-Knitting Machines, of which the following is a specification.

The object of this invention is the production of means for simplifying and expediting the operation of transferring the top of a stocking from a machine adapted to knit an elastic ribbed fabric, such as is commonly used for the tops of stockings, to a knitting-machine arranged to continue the knitting operation, usually to complete the stocking.

In knitting stockings on circular-knitting machines the ribbed top of the stocking is usually made separately and transferred from the machine upon which it is knit to the machine that forms the leg and foot of the stocking and narrows and widens for the heel and the toe. In transferring the ribbed top from one machine to the other a device for placing each one of the stitches of the ribbed top upon a needle of the second knitting-machine is necessary. Such a device is provided in what is called a "transfer-ring," and this ring usually comprises two rings, one fitting tightly upon the periphery of the other. The inner ring is provided in its peripheral face with grooves formed nearly parallel with its central axis, and in each of these grooves is set a semitubular piece of steel sharpened at one of its ends by being cut off obliquely to its length, its other end being cut off squarely. These semitubular pieces are called "quills." They are of a uniform length and are set in the grooves in the inner ring, so that their square ends are flush with one side of said ring and are held in place by forcing the second ring over the first and securing it in position in any suitable way. The quills are usually set into their grooves, so that their concave faces are disposed outward, though rings are sometimes formed with the concave sides of the quills facing inward. However this may be, the number of quills in the transfer-ring must agree with the number of needles in the cylinder of the machine to which said ribbed top is to be transferred for

the continuation of the knitting operation. In transferring the ribbed top to the second knitting-machine the unfinished or bottom end of said top is stretched over the points 55 of the quills of a transfer-ring, the stitches of said top being slipped over said quills. The transfer-ring is then inverted over the upper ends of the needles of the second knitting-machine and each needle placed within the 60 concavity of one of the quills in order that when all the needles are in place within the quills the stitches of the knitted top may be stripped downward over said needles. This method of transferring takes much time not 65 only of the operative, but of the knitting-machine, as on account of slight irregularities in the positions of the upper ends of the needles much difficulty is experienced in placing the needles within their corresponding quills. 70

The object of this invention, therefore, is accomplished by spacing the upper ends of the needles uniformly with relation to their circular arrangement, as well as with reference to their vertical position, so that the 75 quills of the transfer-ring may simply be set over the tops of the needles and each needle will be in position to be raised within its corresponding quill. In the embodiment herein shown of this invention this object is attained 80 by switching the needles so that their shanks rest upon the ledge in the cam-ring, the tops of the needles being in a horizontal plane. The needle-cylinder is now raised bodily, the needles being held from movement with said 85 cylinder or being depressed after the movement thereof, so that their shanks are in contact with said ledge and so that the upper ends of said needles project but slightly above the upper edge of the needle-cylinder. 90 The needle-grooves being regularly disposed in the needle-cylinder and the tops of the needles being level, the transfer-ring may readily be put in place, each one of the quills lying between adjacentsinker-slides, and consequently just inside of and over the top of one of the needles. The lower ends of the quills rest upon the top of the needle-cylinder, and when the latter is lowered to its normal or operative position the transfer-ring 95 slides downward therewith upon the needles until it is sustained upon the tops of the lat-

ter. In this latter position the ribbed top may be drawn downward through the interior of the cylinder, the stitches of the top being stripped from the quills of the transfer-ring onto the 5 needles.

In the accompanying drawings, Figure 1 is a vertical central section through a knitting-machine embodying the features of my invention, showing the cylinder elevated and 10 the needles out of alinement. Fig. 2 is a similar view showing the needles after they have been alined by the leveling-plate and after the transfer-ring has been placed in position upon the tops of the needles. In this view 15 the ribbed-top fabric is represented as being ready to be stripped downward from the quills of the transfer-ring to the knitting-needles. Fig. 3 is a fragmental view showing the lower end of the needle-cylinder in ele-20 vation. Fig. 4 is a vertical central section through the cam-ring, showing the switch for elevating the needles from the cam-groove onto the horizontal needle-ledge. Fig. 5 is a fragmental vertical section taken through 25 the switch shown in the preceding figure. Fig. 6 is a fragmental view showing in elevation the switch illustrated in Figs. 4 and 5. Fig. 7 shows the means for supporting the 30 hand-lever provided for raising and lowering the needle-cylinder, also showing the pivotal supports for said lever.

In the construction of this knitting-machine I provide a supporting-frame A, having the bed A'. The supporting-frame carries 35 the driving-shaft A², having the driving-gear A³, rigidly mounted thereon, and the bed A' supports a tubular post A⁴, formed integral therewith, also a post A⁵ for sustaining the yarn-guiding mechanism. (Not shown.) A 40 hand-lever A⁶ is pivotally mounted upon a screw-stud A⁷ in a bracket A⁸, depending from the bed A', which hand-lever has a stud A⁹ projecting from its side for engaging the needle-cylinder, the purpose of the lever being 45 to raise and lower the cylinder, as will hereinafter more fully appear.

B is the needle-cylinder, having the usual needle-grooves B' in the periphery thereof, which grooves are adapted to receive the 50 needles B², each of which latter is provided with a shank B³ for engaging the cam-groove in the cam-ring. The lower edge of the needle-cylinder has a triangular cam-notch B⁴, adapted to receive the stud A⁹ of the hand-le- 55 ver A⁶. When the lever is oscillated, the stud A⁹ engages the inclined cam-surface of said angular notch B⁴, giving the cylinder a greater vertical movement than it otherwise would receive.

C is a cam-ring surrounding the needle-cylinder, rotatably mounted on the bed A' of the supporting-frame A and arranged to be driven by the gear-wheel A³, which meshes with gear-teeth C' on the under side of said 60 cam-ring. The cam-ring C has the usual cam-groove C² therein for receiving the shanks

B³ of the needles and operating the latter to knit, also the usual ledge C³, upon which the needles rest when not in said cam-groove. A vertically - elongated opening C⁴ in said cam-ring is provided with a sliding switch-block C⁵. On the inner side of the cam-ring this switch-block carries the transverse member C⁶ and the pivoted tongue C⁷. A locking-latch C⁸ is pivoted to said sliding block on 70 the outside of said cam-ring, which latch is adapted to engage the fixed stud C⁹ on said ring and hold said switch in either one of its two positions. A spring C¹⁰, connected with said latch, holds the latter in engagement 80 with said stud.

A sinker-slide bed D is rigidly secured to the upper end of the needle-cylinder B. It has the usual radial grooves D' with the sinker-slides D² therein, each of which latter 85 is provided with an upwardly-projecting lug D³ for engaging the cam-groove D⁴ in the cam-ring D⁵ for operating said sinker-slides.

E is a leveling-plate for engaging the upper ends of the needles B². It is supported in 90 the sleeve E' at the outer end of the arm E², the integral upright portion of which arm lies in the tubular post A⁴ and has an oscillatory movement therein. The leveling-plate E is provided with a central stem E³, having a 95 vertically - reciprocatory movement in said sleeve E', and said stem is provided with a stud E⁴, adapted to slide in the vertical groove E⁵ in the sleeve E'. This groove has an off-set portion E⁶ for locking the stem E³ in its 100 lowest position, the stem being normally held elevated by the action of the spring E⁷, surrounding said stem. The arm E² is adapted to be turned in its supporting tubular post A⁴ into coincidence with the needle-cylinder 105 B when it is desirable to level the tops of the needles to receive the transfer-ring, or it may be swung to one side when not in use. A projection E⁸, extending from the side of the arm E², engages the post A⁵ to stop the leveling-plate directly over the needle-cylinder B. 110

F is a transfer-ring composed of the inner ring F', having grooves F² therein, semitubular quills F³, adapted to lie in said grooves, and the outer ring F⁴ for securing said quills 115 rigidly in place in said grooves. The quills slant inward slightly, the more readily to fit over the tops of the needles when said transfer-ring is placed in position upon the needle-cylinder. 120

G represents the ribbed top for a stocking, the stitches of the lower end of which top are drawn over the quills of the transfer-ring.

The operation of this knitting-machine is in general like that of other machines of its 125 type. When it is desired to present a ribbed top to the needles of the machine, the locking-latch C⁸ of the vertically-movable switch-block C⁵ is rocked upon its supporting-pivot to withdraw said latch from engagement with 130 the fixed stud C⁹. The switch-block is then elevated, its fixed member C⁶ preventing the

needles from descending into the cam-groove C² of the cam-ring C, retaining said needles in a horizontal plane. The hand-lever A⁶ is then raised, lifting the needle-cylinder bodily upward. By reason of the friction existing between the needles and the needle-cylinder most of the needles will also be raised with the cylinder, though those that are loose in their grooves will remain with their shanks in contact with the ledge C⁸ of said cam-ring. The leveling-plate E is then swung into coincidence with the needle-cylinder and said plate depressed against the action of its supporting-spring E' by the hand of the operator. The leveling-plate pushes all the needles downward, so that their tops lie substantially on a level with the tops of the sinker-slides D², projecting slightly above the upper edge of the needle-cylinder. A transfer-ring, upon the quills of which the stitches of the ribbed top have been drawn, is next placed upon the top edge of the needle-cylinder, so that each of said quills stands with its lower end between two of the sinker-slides D². This will bring each of the quills into exact coincidence with one of the needles of the cylinder B. By depressing the hand-lever A⁶ the needle-cylinder will be lowered to its normal or knitting position, and the transfer-ring resting upon the upper end of said needle-cylinder will follow said needle-cylinder downward until its weight is sustained by the needles. The stitches upon the quills of the transfer-ring may then readily be transferred to the needles by pulling downward upon the ribbed top and stripping said stitches from the quills to the needles. When this is done, the transfer-ring is removed, the locking-latch C⁸ withdrawn from engagement with the fixed stud C⁹, and the switch-block C⁵ depressed, opening the cam-groove to receive the needle-shanks when the cam-ring C is rotated. The machine is now in a position to knit a continuation of the ribbed top. The offset E⁶ in the elongated opening E⁵ is provided, so that the leveling-plate E may be depressed and held in that position. When the leveling-plate is used in this manner and it is desired to put a ribbed top onto the needles of the machine, the plate is moved into coincidence with the cylinder before the same is elevated. The plate thus acting as a stop occupies a position which will prevent the needles from rising with the needle-cylinder.

I claim as my invention—

1. A knitting-machine comprising a needle-cylinder having needle-grooves therein; needles free to slide in said grooves; a cam-ring having a ledge for limiting the downward movement of said needles; means for bodily raising said needle-cylinder; and a plate for leveling the tops of the needles in a plane slightly above the top of the needle-cylinder to receive a transfer-ring.
2. A knitting-machine comprising a needle-

cylinder having needle-grooves therein; needles free to slide in said grooves; a cam-ring having a ledge for limiting the downward movement of said needles; means for bodily raising said needle-cylinder; a plate; and means whereby said plate may be vertically reciprocated for leveling the tops of the needles in a plane slightly above the top of the needle-cylinder, to receive a transfer-ring. 75

3. A knitting machine comprising a needle-cylinder having needle-grooves therein; needles free to slide in said grooves; a cam-ring having a ledge for limiting the downward movement of said needles; means for bodily raising said needle-cylinder; an arm adapted to be swung over said needle-cylinder; and a plate for leveling the tops of the needles in a plane slightly above the top of the needle-cylinder, which plate is slidably mounted on 85 said arm.

4. A knitting-machine comprising a bed-plate; a needle-cylinder having needle-grooves therein; needles free to slide in said grooves; a cam-ring having a ledge for limiting the downward movement of said needles; a lever for bodily raising said needle-cylinder; an arm pivotally mounted upon the bed-plate, and adapted to be swung over said needle-cylinder; a spring-plunger mounted 95 in said arm; and a plate on said plunger for leveling the tops of the needles in a plane slightly above the top of the needle-cylinder.

5. A knitting-machine comprising a bed-plate; a needle-cylinder having needle-grooves therein; needles free to slide in said grooves; a cam-ring having a ledge for limiting the downward movement of said needles; a bell-crank lever for bodily raising said needle-cylinder; an arm pivotally mounted on 100 said bed-plate, and adapted to be swung over said needle-cylinder; a plunger mounted in said arm; a spring for holding said plunger elevated; a plate on said plunger, for leveling the tops of the needles in a plane slightly above 110 the top of the needle-cylinder; and means for holding said plate downward against the action of the spring of said plunger.

6. A knitting-machine comprising a bed-plate; a needle-cylinder having needle-grooves therein; needles free to slide in said grooves; a cam-ring having a ledge for limiting the downward movement of said needles; a bell-crank lever for bodily raising said needle-cylinder; a stud on said lever, for engaging said cylinder; an arm pivotally mounted upon the bed-plate, and adapted to be swung over said needle-cylinder; a plunger mounted in said arm; a spring for holding said plunger elevated; a stud on said plunger for holding it downward against the action of said spring; and a plate for leveling the tops of the needles in a plane slightly above the top of the needle-cylinder. 125

7. A knitting-machine comprising a bed-plate; a needle-cylinder having needle-grooves therein, and a cam-surface near its

lower end; needles free to slide in said grooves; a cam-ring having a ledge for limiting the downward movement of said needles; means adapted to act upon the tops of the 5 needles for leveling said tops; a lever pivotally mounted upon said bed-plate, for vertically moving said needle-cylinder; and a stud on said lever, for engaging the cam-surface in said needle-cylinder.
